UNITED STATES PATENT OFFICE.

FREDERICK J. SCHNORR, OF TWO RIVERS, WISCONSIN.

SPECTACLE-CASE.

1,004,474.

Specification of Letters Patent. Patented Sept. 26, 1911.

Application filed March 13, 1911. Serial No. 614,147.

To all whom it may concern:

Be it known that I, FREDERICK J. SCHNORR, a citizen of the United States, residing at Two Rivers, in the county of Manitowoc and State of Wisconsin, have invented 5 certain new and useful Improvements in Spectacle-Cases, of which the following is a specification, reference being had therein to the accompanying drawing.

10 This invention relates to cases for eye glasses and spectacles, and has for its object to provide an improved case which is formed with two receptacles for glasses located back to back to each other and a pair 15 of covers each closing one of said receptacles.

Referring to the accompanying drawings:—Figure 1 is a view in perspective of a case for eye glasses, constructed in accordance with this invention, and showing the two covers open. Fig. 2 is a plan view of a blank of sheet metal cut out to form the eye glass case before it is folded into shape to complete the construction of the eye glass 25 case. Fig. 3 is an end view in cross section of the eye glass case with the covers closed. Fig. 4 is an enlarged detail view in perspective showing the upper side of the case with the covers detached, and partly 30 broken away.

In carrying out the invention, a blank of sheet metal is cut out to form an oblong central portion 1 having the projecting rounded ends 2 and adjacent to each end 35 on each side a projection 3 consisting of a narrow strip with a rectangular opening 3' on one side of said strip. The blank further is formed with a strip 4 at each side of the central strip 1 and parallel thereto, 40 said strip 4 having at each end pairs of projecting strips 5, there being located between each pair of strips 5 a rectangular opening 6. Connected with each set of strips 5 is an oblong blank 7 with rounded ends 8 and 45 somewhat similar in size to the oblong blanks 1, and adapted to serve as a cover for the eye glass case. Located between the strip 4 and the blank 7 is an oblong rectangular space 7'. The blank is severed by 50 short cuts indicated by the lines 9 and 10 to form a strip 11 similar to the strip 3 and the several strips 3 are severed at one end as indicated by the line 12. The strips 5 are 55 severed from the longitudinal strip 4 at the lines indicated by 13. The several separate blanks thus provided are then bent and se-

cured together as follows:—Each of the blanks 7 serves as a cover for the eye glass case. Each of the strips 4 is bent over the central blank 1 to the position shown in Fig. 4, and each end of the strip 4 is bent to form the depending portion 14 which abuts against the central blank 1, said strip 4 so bent serving as a pocket for a pair of eye glasses. Each of said strips 4 is bent toward the opposite side of the blank 1. The central blank 1 is provided at each end with a slit 15 whereby the severed portions of each end of said blank may be bent over in opposite directions at an angle to said blank to form the ends 16 and 17 of the two receptacles on each side of said blank 1. The strips 3 are bent to form tubular hinge sockets 18 and the strips 5 are bent to form pairs of tubular hinge sockets 19, each of the tubular hinge sockets 18 being located between and in alinement with a pair of tubular sockets 19 and the cover 7 is hinged to the eye glass case by means of a rod extending through said tubular hinge sockets. The strips 11 are each bent to form a tubular socket 20.

A suitably shaped spring 21 is provided which bears against the inner side of each cover 7 and has torsional spring ends, each of said ends being mounted in a tubular socket 20. Each of the springs 21 serves to snap the cover 7 into open or closed position and to hold it in either of said positions.

It will be noticed that oblong openings 22 are formed between each strip 4 and the adjacent edge of the blank 1 thereby permitting certain of the tubular sockets 19 to be seated therein and to freely rotate.

The several parts of the case hereinbefore described are covered with a suitable covering 28 which extends over and closes the several gaps in the casing shown in Fig. 4 as well as over the hinged portions of the casing and the springs as shown in Fig. 1.

It will be seen that by means of a case constructed as hereinbefore set forth and as shown in Fig. 1 an eye glass case is provided which is formed with two receptacles back to back to each other and separated by a longitudinal partition with a cover on each side of the casing to cover each of said receptacles.

Having described the invention, what I claim is:—

A double eye glass case formed from a sheet metal blank consisting of an oblong

central portion having rounded ends with a short slit in the center of each end, said oblong central portion forming a partition between the two eye glass receptacles of the case, the slotted portions of the end of the oblong central portion being bent in opposite directions at an angle thereto to form the ends of the two receptacles on each side of the partition, the oblong central portion of the blank being also formed on each side adjacent to each end with a short narrow strip spaced apart from each other and bent in opposite directions to form tubular sockets for the hinges, and also with a lateral projection on each side having at its outer end a transverse strip, each of said lateral projections and said transverse strip being bent over on opposite sides of said central oblong portion with the ends of said transverse strip bent at an angle to form

therewith a pocket in each eye glass receptacle; said blank being further formed with two oblong portions having rounded ends similar to the central oblong portion and having adjacent to each end thereof on one side laterally projecting strips spaced apart from each other and bent into a tubular shape to form sockets located in alignment with the tubular sockets in the main portion of the blank to form hinges therewith, 25 said oblong hinged portions being formed of a concave shape, and each closing respectively one of the eye glass receptacles on each side of the partition.

In testimony whereof I hereunto affix my signature in presence of two witnesses.

FREDERICK J. SCHNORR.
